UNITED STATES PATENT OFFICE.

HENRY DOTZENROTH, OF PITTSBURG, PENNSYLVANIA, ASSIGNOR TO
LEOPOLD W. VILSACK, OF SAME PLACE.

DESIGN FOR A BADGE.

SPECIFICATION forming part of Design No. 25,688, dated June 30, 1896.

Application filed March 26, 1896. Serial No. 585,028. Term of patent 3¹ years.

To all whom it may concern:

Be it known that I, HENRY DOTZENROTH, a resident of Pittsburg, in the county of Allegheny and State of Pennsylvania, have invented and produced a new and original Design for a Badge; and I hereby declare the following to be a full, clear, and exact description thereof, reference being had to the accompanying drawing, in which the figure 5 shown shows a plan or face view of my design for badges.

My design for a badge consists in a heraldic shield, upon the surface of which is a lyre, while running back of the lyre, at an angle, is 10 a clarinet. Running across, at an angle, in front of one side of the lyre and under the opposite side thereof, is a flowing band having overlying ends. A branch or wreath-

ing is run around on either side of the lyre, clarinet, and band.

The design, as set forth and illustrated in the drawing, is held suspended by a link to an upper flowing band having overlying ends, the upper and lower central portion of which band being embellished with scroll ornamentation. 20

What I claim is—

The design for a badge, substantially as herein shown and described.

In testimony whereof I have hereunto set 30 my hand.

HENRY DOTZENROTH.
